UNITED STATES PATENT OFFICE

LEWIS A. MAPEL, OF ST. LOUIS, MISSOURI, ASSIGNOR TO MECHANICAL DEVELOPMENT COMPANY OF MISSOURI, OF ST. LOUIS, MISSOURI, A CORPORATION OF MISSOURI.

DESIGN FOR AN ELECTRIC TIME-SWITCH AND INDICATOR.

49,436.

Specification for Design.

Patented July 25, 1916.

Application filed May 15, 1916. Serial No. 97,750. Term of patent 14 years.

To all whom it may concern:

Be it known that I, LEWIS A. MAPEL, a citizen of the United States, residing at St. Louis, Missouri, have invented a certain new, original, and ornamental Design for an Electric Time-Switch and Indicator, of which the following is a specification, reference being had to the accompanying drawing, forming part thereof.

Figure 1 of the drawings is a front ele-

vational view; and Fig. 2 is a top plan view of my new design for an electric time switch and indicator.

I claim:

The design for an electric time switch and indicator, as shown.

LEWIS A. MAPEL.

Witnesses:

WELLS L. CHURCH,
GEORGE BAKEWELL.
